POURING HANDLE FOR A MILK CARTON

Herman Epstein, 1210 E. 9th St.,
Kansas City, Mo. 64106

Filed June 27, 1966, Ser. No. 2,816

Term of patent 7 years

(Cl. D44—21)

FIG. 1 is a side elevational view of a pouring handle for a milk carton showing my new design, with a milk carton shown fragmentarily in broken lines for illustrative purposes only,

FIG. 2 is a front elevational view thereof,

FIG. 3 is a rear elevational view thereof, and

FIG. 4 is a top plan view thereof.

I claim:

The ornamental design for a pouring handle for a milk carton, as shown and described.
